United States Patent Office

Des. 181,168
Patented Oct. 8, 1957

181,168

SPOON OR SIMILAR ARTICLE OF FLATWARE

Mary C. Suhren, Orlando, Fla.

Application January 10, 1957, Serial No. 44,470

Term of patent 14 years

(Cl. D54—12)

Fig. 1.

Fig. 2.

Fig. 3.

I claim:

The ornamental design for a spoon or similar article of flatware, as shown.
